UNITED STATES PATENT OFFICE.

RICHARD W. MCQUEARY, OF GRANBY, COLORADO.

CULVERT.

1,362,952.

Specification of Letters Patent. Patented Dec. 21, 1920.

Application filed November 3, 1919. Serial No. 335,381.

To all whom it may concern:

Be it known that I, RICHARD W. MCQUEARY, citizen of the United States, residing at Granby, county of Grand, and State 5 of Colorado, have invented certain new and useful Improvements in Culverts; and I do declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to culverts to be used particularly on mountain roads.

The object of the invention is to provide a structure whereby water flowing down ruts on inclined roads may be intercepted. Also, 20 it is an object to deflect water from the high side of the road to the low side at the same time.

Briefly, the invention comprises a split cylinder adapted to be positioned in the 25 roadbed with the slit uppermost to receive water from the crown of the road, the opposed edges of the cylinder having reversely turned horizontal tread plates adapted to lie flush with the road surface. At least one 30 end of the cylinder is cut out at one side for a short distance in order that the projecting side may be set across the ditch at the high side of the road to intercept water coming into the cylinder through the cut-out portion 35 and to deflect it across the road.

In the drawing:

Figure 1 is a perspective, showing the use 40 of the device;

Fig. 2 is an end view indicating the positioning of the same.

The culvert is in the form of a split cylinder 10, the split being indicated at 12 and being only two or three inches wide, so that traffic will not be interfered with. The tread 45 plates 14 and 16 are turned back from the opposing edges of the cylinder at the split, these plates being flush with the crown of the road. As shown in the drawings, each end of the cylinder is cut back at the lower 50 side to about the point indicated at 18, thereby forming a projecting corner or lip 20. The upgrade side of the cylinder at each end is cut on a line 22 in a vertical plane to leave an opening projecting upgrade. If desired, 55 this cut may extend entirely to the lowest side of the cylinder, thereby partially sever-

ing the lip 20 so that it may be flattened down in order to guide the incoming water through the culvert. If desired, an overhanging flange 24 may be provided on the 60 tread plate 14 to overhang the cutout portion for sake of appearance. The culvert is preferably mounted in concrete 26, as indicated in Fig. 2, in order to make the device more substantial and rigid against traffic. 65

When both ends of the culvert are cut out as indicated at 18 and 22, the same structure may be used whether the high side of the road is on the right or on the left, but it is obvious that only one end may be so constructed, requiring two designs of culverts 70 cut out on opposite ends.

As shown in Fig. 1, the left end of the culvert is positioned against the bank of the ditch or hillside, while the opening 75 on the opposite side extends upgrade to receive the water which is intercepted by the projecting side and deflected through the culvert to the low side. The grade of the road is indicated by the arrows. The cutout 80 portion on the right-hand side has no function, as this is provided merely in order that the culvert may be used for slope in either direction. Water coming down the road in the ruts will fall into the culvert through 85 the slit 12 and run to the side of the road. Water coming down the ditch on the high side flushes out any sand and dirt which is deposited in the culvert through the slit 12 and in this way the culvert is always kept 90 clear.

These culverts are placed in the road at frequent intervals and in this manner washing on long stretches of rutty, downgrade road is prevented. In this manner road up- 95 keep is materially reduced.

I claim:

1. A culvert comprising a split sheet metal cylinder, the split being located at its upper side to receive water from the crown of the 100 road, said split being too narrow to interfere with traffic, and oppositely extending horizontal tread plates connected with the edges of the cylinder at the split.

2. A culvert comprising a split thin walled 105 cylinder, the split being located at its upper side to receive water from the crown of the road, said split being too narrow to interfere with traffic, and oppositely extending horizontal tread plates connected with the 110 edges of the cylinder at the split, said culvert being mounted in concrete and said

tread plates adapted to be positioned on the level of the road surface.

3. A culvert having one side at one end projecting beyond the other side at that end, said projecting side being adapted to be set in a ditch to deflect down-coming water through the culvert.

4. A culvert having a narrow opening at its upper side to receive water from the 10 crown of the road, said opening being too narrow to interfere with traffic, one side of said culvert at one end projecting beyond the other side at that end and being adapted to be set in a ditch to deflect down-coming 15 water through the culvert.

5. A culvert comprising a split sheet metal cylinder, the split being located at its upper side to receive water from the crown of the road, said split being too narrow to inter-

fere with traffic, one side of said culvert at 20 one end projecting beyond the other side at that end and being adapted to be extended into a ditch to deflect down-coming water through the culvert.

6. A culvert comprising a split thin walled 25 cylinder, the split being located at its upper side to receive water from the crown of the road, said split being too narrow to interfere with traffic, and oppositely extending horizontal tread plates connected with the edges 30 of the cylinder at the split, one side of said culvert at one end projecting beyond the other side at that end and being adapted to be extended into a ditch to deflect down-coming water through the culvert. 35

In testimony whereof I affix my signature.

RICHARD W. McQUEARY.
